UNITED STATES PATENT OFFICE.

ROBERT WINFIELD BAYLEY, OF BROOKLYN, NEW YORK, ASSIGNOR TO BAYLEY & SONS, INC., OF BROOKLYN, N. Y., A CORPORATION OF NEW YORK.

LIGHTING UNIT.

1,391,235.

Specification of Letters Patent. Patented Sept. 20, 1921.

Application filed July 31, 1919. Serial No. 314,553.

To all whom it may concern:

Be it known that I, ROBERT WINFIELD BAYLEY, a citizen of the United States, residing in the city of Brooklyn, county of 5 Kings, and State of New York, have invented a certain new and useful Improvement 10 in Lighting Units, of which the following is a specification.

My invention relates to an improvement 15 upon the present type of individual lighting units which are termed combined semi and total indirect lighting units. These units, as is well known to persons skilled in the art, are designed first to overcome the deleterious 20 effect upon the human eye of the intense brightness emitted by the newer type of gas filled or so called nitrogen lamps and which accomplish this by the use of a so called indirect fixture, the unnatural effect in a room produced by this type of fixture being remedied by permitting a portion of the light to escape into a translucent shield or glass bowl.

Devices of this kind, with which I am 25 familiar, are lacking in efficiency.

My invention has for its object to provide 30 a lighting unit in which there will be combined indirect, semi-indirect and flood lighting, which will be so combined as to greatly increase the efficiency of the lighting unit and thereby effect greater economy.

One of the objects of my lighting unit is 35 to control the rays emitted by the source of light and to direct the rays so that a larger area of illumination is obtained from the upper side of the indirect reflector directly upon the ceiling by direct reflection to control and direct the illumination of a large area laterally by the flood light directed from the source of light against the under 40 side of the upper reflector and the upper side of an intermediate reflector thereby increasing the efficiency of the illumination on the working plane and to provide means for diffusing the direct rays emitted by the 45 source of light in passing either directly or through the medium of the total indirect or the upper reflector through the ceiling or through the laterally flood lighting so that the illumination of the working plane directly beneath the fixture will be materially increased.

My means of accomplishing the foregoing 50 objects may be more readily comprehended

by having reference to the accompanying drawings which are hereunto annexed and 55 are a part of this specification in which—

Figure 1 is a side elevation of my improved lighting unit, one-half being shown in section.

Figs. 2 and 3 are similar views of the 60 modified forms of construction.

Similar reference numerals refer to similar parts throughout the entire description.

As shown in the drawings, the unit comprises an upper or total indirect reflecting 65 member 10 which is preferably made of suitable non-inflammable material such as enameled steel or it may be made of glass, the enameled steel is in my opinion preferable, but I do not desire to be limited to 70 that material. This reflector is in the shape of an inverted cone and is provided with a radially extending flange 20, which is especially desirable when the light is to be directed downwardly within a given space, 75

although the fixture will be operative if the upper reflecting member is formed as shown in Fig. 2. This reflector 10 is secured to a canopy or socket cover 11 by means of links 12 which are attached to the lower edge of 80 the socket cover 11 by means of hooks 13 in the usual manner and are provided with eyes at their outer ends which are adapted to engage hooks 14 which are formed on the connecting member 15. As seen in the sectional 85 view, this member extends to the lower edge of the reflector 10 and then is bent downwardly until it is brought into engagement with the inner surface of the intermediate reflector 16, whence it extends downwardly 90 and around the lower edge of the intermediate reflector 16 and extends radially terminating in a lip engaging member 17. These connecting members are made of flexible material which will expand on pressure so 95 that they can be spread sufficiently to engage the lip of the translucent glass bowl 18 and will contract so as to engage with sufficient pressure the outer edge of the translucent bowl and thus hold it in position. An electric lamp bulb 19 is mounted in the canopy, as shown it is the well known type C or 100 nitrogen lamp. It frequently happens that the user desires to employ a different sized bulb in the fixture, but inasmuch as the fixture is adjusted so as to have the source of

light in a particular position it is not practical to change the bulb. I have provided means to overcome this by equipping the connecting member 15 with a ring 21 which 5 will enable the use of a larger bulb when desired and still bring it into the proper functioning position with relation to the reflecting members.

It will be apparent from an inspection of 10 the drawings in connection with the foregoing description that a unit thus constructed in which both the upper reflector 10 and the intermediate reflector 16 are so constructed that both their upper and lower 15 surfaces form efficient reflecting media that the objects set forth hereinbefore are fully accomplished by my device.

Having described my invention what I regard as new and desire to secure by Letters 20 Patent of the United States is:

1. A lighting fixture comprising the combination with a source of light of an upper member, both sides of said member being adapted to serve as reflectors, a translucent 25 bowl below the upper member and flexible means to support said bowl and members in spaced relationship so that a portion of the direct light rays will reach the ceiling, a portion will be reflected upward from the surface 30 of the upper member, a portion of the direct rays will escape laterally as a flood light intermediate the lower surface of the upper member and the upper surface of the bowl and thence to the working plane.

35 2. A lighting fixture comprising the combination with a source of light of an upper member, an intermediate member, both sides of said members being adapted to serve as reflectors, a translucent bowl below the intermediate member, means to support said bowl and members in spaced relationship so that a portion of the direct light rays will 40 reach the ceiling, a portion will be reflected upward from the surface of the upper member, a portion of the direct rays will escape laterally as a flood light intermediate the lower surface of the upper member and the upper surface of the intermediate member and thence to the working plane.

45 3. A lighting fixture comprising the combination with a source of light of an upper member, an intermediate member, both sides of said members being adapted to serve as reflectors, a translucent bowl below the intermediate member, means to support said bowl and members in spaced relationship so that a portion of the direct light rays will 50 reach the ceiling, a portion will be reflected upward from the surface of the upper member, a portion of the direct rays will escape laterally as a flood light intermediate the lower surface of the upper member and the upper surface of the intermediate member, and a portion of the light rays will 55 strike the upper surface of the intermediate 60 member and be reflected to the lower surface of the upper member and redirected thence to the working plane.

4. A lighting fixture comprising the combination with a source of light of an upper 70 conoidal member, having a radial flange, an intermediate member, both sides of said members being adapted to serve as reflectors, a translucent bowl below the intermediate member means to support said bowl 75 and members in spaced relationship, so that a portion of the direct light rays will reach the ceiling, a portion will be reflected upward from the surface of the upper member, a portion of the direct rays will pass 80 below the lower surface of the upper reflector and strike the lower surface of the flange and be reflected downwardly to the working plane.

5. A lighting fixture comprising the combination with a source of light, a socket in which it is mounted, a canopy inclosing said socket, of an upper conoidal member, having a radial flange, both sides of said member being adapted to serve as reflectors, a 90 translucent bowl below the upper member, means to support said bowl and members in spaced relationship from the canopy so that a portion of the direct light rays will reach the ceiling, a portion will be reflected upward from the surface of the upper member, a portion of the direct rays will pass below the lower surface of the upper reflector and strike the lower surface of the flange and be reflected downwardly to the working 95 plane.

6. A lighting fixture comprising the combination with a source of light of an upper conoidal member, having a radial flange, an intermediate member, both sides of said members being adapted to serve as reflectors, a translucent bowl below the intermediate member, means to support said bowl and members in spaced relationship, so that a portion of the direct light rays will reach 105 the ceiling, a portion will be reflected upward from the surface of the upper member, a portion of the direct rays will pass below the lower surface of the upper reflector and strike the lower surface of the flange and be reflected downwardly to the working 110 plane, and means secured to said supporting means to adjust their position with relation to the canopy.

7. A lighting fixture comprising the combination with a source of light, a socket in which it is mounted, a canopy inclosing said socket, of an upper member, which member flares upwardly and outwardly and is provided with a circumferential flange which 125 curves downwardly, both sides of said member being adapted to serve as reflectors, a translucent bowl below the upper member, means to support said bowl and members in spaced relationship from the canopy, said 130

supporting means being resilient at the point of the engagement with the translucent bowl, the spaced relationship being such that a portion of the direct light rays will reach the ceiling, a portion will be reflected upward from the surface of the upper member, a portion of the direct rays will pass uninterrupted between the bowl and the lower

surface of the upper member, and a portion of the light rays will strike the lower surface of the flange and then be reflected downwardly to the working plane, and another portion will strike the bowl and be redirected to the lower surface of the upper member when it will pass to the working plane. 10 15

ROBERT WINFIELD BAYLEY.
